EDWIN S. RIGDON, OF BEREAL, OHIO.

SHOE-SUPPORT.

1,221,092.

Specification of Letters Patent.

Patented Apr. 3, 1917.

Application filed July 27, 1914. Serial No. 853,313.

To all whom it may concern:

Be it known that I, EDWIN S. RIGDON, a citizen of the United States, residing at Berea, in the county of Cuyahoga and State 5 of Ohio, have invented certain new and useful Improvements in Shoe-Supports, of which the following is a specification.

This invention relates to a device adapted to support a shoe for the purpose of polishing the same, all substantially as shown and described and particularly pointed out in the claim.

In the accompanying drawings, Figure 1 is a plan view of the device, and Fig. 2 is a 15 side elevation thereof, and of a part of a table to which it is attached. Fig. 3 is an end elevation and Fig. 4, a perspective detail of the post or standard upon which the device is supported.

20 The conception herein involves a convenient mechanism for receiving a shoe to polish the same when removed from the foot, and its essential details comprise means for gripping the sole and heel of the shoe 25 to hold it firmly while otherwise the shoe is bodily exposed to be polished by the usual or suitable means, the post or standard *s* being of a length to give the shoe the desired elevation from a table *t* or other support.

30 The immediate shoe engaging members consist in the two curved or segmentally shaped arms *a* having clamping jaws 2 at their outer ends adapted to engage over or upon the edge of the sole of the shoe at 35 opposite sides back some distance from the toe, while the heel member *h* is a plate having heel engaging jaws 3 and is provided with two outer parallel slots 4 and a central slot 5 serving as a medium for adjusting 40 said heel plate back and forth in respect to the fixed plate 6 and which plates are in loose or slideable relations with each other through the headed rivets 7; that is, the heel plate is slideably supported on the fixed 45 plate 6.

At the opposite end of the device, the clamping arms *a* have segmental slots 8 engaged by free rivets 9 with the fixed front plates 10 and slideable thereon, and the two 50 plates 6 and 10 with the curved or crescent shaped support 12 are rigid with each other and practically constitute a frame on which the arms *a* and heel plate *h* are slideably mounted within variable limits and according to the size of the shoe to be polished.

To these ends, the said parts *a* and *h* are

provided with swivel studs 15 and 16 respectively, the stud 15 being engaged through the overlapped ends of the clamping arms *a* and the stud 16 being fixed eccentrically in the lever *d* at 17 while the lever itself is pivoted at 18 on the inner extremity of fixed plate 6. An adjusting screw 20 with reverse threads on its ends engages through the studs 15 and 16, which serve in 60 a sense as nuts to adjust the parts *a* and *h* to correspond substantially to the size of shoe to be polished, after which the inward closing of the lever *d* will finish the clamping upon the shoe. Thus, in Fig. 3, the position of lever *d* indicates that the clamps for the shoe are open. Then upon swinging the 65 said lever on its pivot 18, the eccentric connection 17 will be swung to its opposite extreme and the shoe will be clamped in the 70 holder. This, of course, assumes that the clamps have been adjusted through the screw 20 to receive a shoe of the size then to be polished, whether of a child or an adult or 75 for man or woman.

The middle slot 5 in heel plate *h* serves as a guide way on the curved support 12 which is made of sheet metal and passes through said slot.

The standard *s* is a separate part and has 80 a clamping jaw and screw 22 at its bottom to affix to a table or the like and an open slot 24 at its top adapted to receive the support 12 edgewise and to be fastened therewith by a set screw 25. By making the said 85 support 12 curved as shown, I can set the holder at different inclinations as seen by full and dotted lines Fig. 2 and by which means one can accommodate the position 90 of the shoe to a given seat by the polisher. Furthermore by clamping the immediate 95 holder on the standard, the said parts are separable for packing and shipping. Ordinarily the standard *s* is about a foot in length. In position the clamping members 100 *a* and *h* are beneath the plates 6 and 10. The fixed heel plate 6 also has a turned up-lip 26 at its inner end and an adjusting screw 27 through said lip to engage the inner shoulder of the heel of the shoe.

The immediate rest for the foot is comprised in the said frame with the plates 6 and 10 and the depending rigid connecting portion or plate 12 which is adjustable in and removable from the standard *s*.

In setting up the device the standard *s* usually is first put in place and then the foot

rest or frame is clamped therein. After this has been done, the parts are adjusted to suit the size of the shoe to be polished and then the manipulation of lever *d* does the balance and the shoe is firmly in the grip of the holder. It is as easily removed by swinging said lever to open position, full lines, Fig. 1.

What I claim is:

- 10 A device to hold shoes to be polished comprising a standard with an open slot vertically in its top, in combination with a foot-rest consisting of two separate horizontally disposed plates spaced apart at the 15 middle of the device and a substantially

crescent shaped support having said plates rigidly fixed upon its ends and adjustably mounted in said slot, clamps for the shoe on the under side of said plates and a rotatable adjusting screw connecting said clamps across the middle of said device and exposed between said plates to be gripped by hand to rotate the same and adapt said clamps to shoes of different sizes. 20

In testimony whereof I affix my signature in presence of two witnesses.

EDWIN S. RIGDON.
